UNITED STATES PATENT OFFICE.

ALBERT H. TINNERMAN, OF CLEVELAND, OHIO.

OVEN-DOOR HINGE.

Application filed July 5, 1924. Serial No. 724,327.

To all whom it may concern:

Be it known that I, ALBERT H. TINNERMAN, a citizen of the United States, residing at Cleveland, in the county of Cuyahoga and State of Ohio, have invented a certain new and useful Improvement in an Oven-Door Hinge, of which the following is a full, clear, and exact description, reference being had to the accompanying drawings.

This invention is directed to improvements in door hinge constructions and particularly to hinge constructions for stove oven doors.

15 The general object of my invention is directed to the provision of a hinge construction for a door or compartment closure means which may be completely concealed when the door is closed. A further object 20 of my invention is the provision of a hinge construction for an oven door which is adaptable for supporting the door in an open position without causing the door to close and which will react on the door when 25 the door is swung from a full open position to close it and maintain it closed.

A further object of my invention is the provision of a hinge construction for pivotally supporting the door upon a shift- 30 able axis whereby the hinge construction may be drawn into the oven closure and thereby permit the marginal edges of the door to come to a uniformly seated position on the oven frame.

35 Other objects of my invention will hereinafter be set forth in the following description referring to the accompanying drawings illustrating a preferred embodiment thereof. The essential characteristics 40 are summarized in the claims.

In the drawings Fig. 1 is a cross section through a stove structure embodying an upper and a lower oven wherein my invention is arranged to support a broiler oven door 45 and a baking oven door; Fig. 2 is an enlarged fragmentary perspective view of the hinge construction showing the relationship of the parts when the door is in a full open position; Fig. 3 is a cross-sectional plan 50 view of the hinge construction illustrating the parts with the door in a full open position; Fig. 4 is a perspective view of the front of an oven structure illustrating the neatness in the appearance of a stove oven

structure which is obtained when provided 55 with my novel hinge construction.

It has been the practice to provide an oven door with a heavy hinge construction usually comprising separable hinge castings bolted or otherwise secured on the outside of the front frame of the oven whereby the door, when opened, may be used as a shelf for supporting a substantial weight. Such hinge constructions involve the use of offset pivotal lugs integrally formed on 65 the door frame and when the door is swung to a closing position, the marginal edges of the door usually fail to make uniform contact with the front frame. Dropping the lugs on the door frame, a considerable 70 distance below the bottom edge of the door supposedly eliminated this closing or sealing deficiency, but this required a heavier hinge construction due to the additional overhang of the door when completely open. 75 This arrangement also resulted in a gap between the door frame and front frame when the door was open. Likewise the incorporation of a spring or some resilient means to cause the door to close when swung 80 from its normally open position, greatly increased the bulk of the hinge construction which detracted from the general appearance of the front of the stove. My invention contemplates a hinge construction which 85 is comparatively light and can be completely concealed when the door is closed and will permit the door to properly seat on the front frame completely around the marginal edges thereof. 90

I show in the drawings an oven structure for a gas stove comprising an oven structure having a partitioning member P dividing the interior of the structure into a baking oven compartment A and a broiler 95 oven compartment B. The burner K is disposed directly beneath the partition member P. Each oven compartment is provided with a door suspended upon my novel hinge construction as will be presently described. 100

A preferred form of my invention comprises two bars 10 extending from the rear to the front of the stove through the oven compartment adjacent the bottom wall 105 thereof. If desired these bars may extend through the door opening or if desired could be concealed by the lining of the oven and

extend through suitable openings formed in the front frame. The embodiment disclosed is of such a simple character that it may be incorporated in the stove, as shown in Fig. 1, in such manner as to be completely concealed by the doors when the doors are closed. I therefore provide hinge lugs 11 adjacent the inner edges of the door frames 12, which may extend upwardly through openings formed in the door linings 13 and these lugs may be secured to the outer ends of the bars 10 by any suitable means such as bolts 14.

I prefer to have the rear ends of the bars 10 rounded and adapted to extend through suitable openings formed in the outer back panel 15, and inner lining panel 16, of the rear wall of the oven and I accordingly reinforce the outer panel 15 with transverse straps 17 through which the ends 10^a of the bars 10 extend. On the rear ends of the bars 10 are spring members 20 held in place by any suitable means such as nut members 21 in threaded engagement with the ends 10^a of the bars whereby the spring members 20 may be placed in position and a desired amount of compression imparted to the springs by adjusting the nuts 21.

As shown in Fig. 2 relation of the front ends of the bars to the lugs 11 is such that the bottom edge 25 of the door frame 12 may abut the lower, or underside of the bars 10 whereby this edge reacts upon the bars to maintain the door in a normally horizontal position as shown in Figs. 1 and 2 and the bars carry the weight of the door in the position shown by resting upon the edge 26^a of the door opening formed in the front frame 26. If desired, side lugs 27 may be provided, extending from the side margins of the front frame door openings to guide the bars 10 along a horizontal path. Such lugs, however, are not essential to the proper functioning of the hinge construction shown.

It will be seen that this simple hinge construction has many advantages over the old form of hinge construction in that when the door is swung to a closing position, there is no fixed pivotal center for the door and the door accordingly can come to a proper seating or sealing relation to the frame 26 around the four edges thereof. Furthermore, when the door is in the open position as shown, the bars 10 serve to maintain the edge 25 of the door against the front frame, thus presenting substantially a continuous surface comprising the oven door lining 13, the door frame edge 25, and the edge 26^a of the front frame, thus greatly facilitating the sliding of utensils into the oven. It will be seen also, that the hinge construction is completely concealed by the door, as shown in Figs. 1 and 4, when the door is being closed and the spring members, disposed at

the rear of the stove, function through the bars to maintain the bars with the edges thereof in proper seated relation to the front frame, while imparting to the bars a uniformity of action which permits a ready and easy swinging of the door when either opening or closing. When the door is completely open the relationship of the lugs 11 and the bars 10 and the reactions thereof upon the front frame 26 is such that the springs do not have any tendency to cause the doors to close in an unexpected manner. In other words, the present hinge construction has the advantage of the usual spring hinge in that the springs have a tendency to overcome the weight of the door when closing the same, but when the door is in an open position it need not be held.

The spring member as shown may be disposed at the rear of the stove remote from the depreciating influence of the heat of the oven and may act through the bars to cause the door to seek a proper seat on the oven frame regardless of any slight imperfections or irregularities in the seating edges of the door frame.

It should be understood that while I have illustrated my novel hinge construction as adapted to the supporting of an oven door for a stove, it, nevertheless, is adaptable to a variety of closure means for compartments such as filing cabinets, lockers, etc.

I claim:

1. A compartment closure means comprising a door, shiftable door supporting means extending through an opening of the compartment including a pivotal connection between the door and said means which is shifted through said opening and resilient means for shifting the door supporting means when the door is swung to a compartment closing position.

2. A compartment closure means comprising a swingable door, retractive pivotal door supporting means projecting through a door opening of the compartment, and resilient means for drawing the door supporting means into the compartment when the door is swung to a closed position.

3. A compartment closure means comprising a door, a shiftable hinge mechanism including a pair of members pivotally supporting the door exteriorly of the compartment and means for drawing said members into the compartment when the door is closed.

4. A compartment closure means comprising a door, pivotal door supporting means extending through an opening of the compartment with the pivotal connection to the door retractively disposed exteriorly of the door when the door is swung to an open position, and resilient means for shifting the door supporting means when the door is swung to a compartment closing position,

said last named means reacting on the door to cause it to seal the compartment completely around the door margin.

5. A compartment closure means comprising a swingable door, pivotal door supporting means projecting from a door opening of the compartment with the pivotal connection to the door exteriorly disposed, and means for drawing the door supporting means into the compartment when the door is swung to a closed position, said means tending to swing the door to a closed position.

6. A compartment closure means comprising a door, shiftable hinge mechanism including a pair of members pivotally supporting the door exteriorly of the compartment and means for drawing said members into the compartment when the door is closed.

7. A door hinge for a stove oven comprising a slidable member pivotally supporting the door and means for retracting said member into the oven structure as the door is closed.

8. A door hinge for a stove oven comprising slidable members pivotally supporting the door and springs for drawing said members into the oven structure as the door is closed.

9. In a stove, an oven structure including a door and a hinge mechanism carrying a shifting pivotal axis for the door slidably mounted in the oven structure and extending through a door opening of the oven.

10. In a stove oven construction, a front frame member having a door opening, a door frame member abutting the front frame member, movable means extending through the door opening for pivotally supporting the door exteriorly of the oven and means for shifting the door supporting means inwardly when the door is swung to a closed position.

11. In a stove oven construction, a front frame member having a door opening, a door frame member abutting the front frame member, and movable means extending through the door opening for pivotally supporting the door with an edge thereof always in contact with the oven frame when the door is swung.

12. In a stove oven construction the combination of a front frame having an oven door opening, a door, means for pivotally supporting the door, said means being slidably relative to the frame and yieldable means acting on the door supporting means to draw the same into the oven when the door is closed.

13. In an oven construction the combination of a front frame member having an oven door opening, an oven door, and a hinge mechanism for the door comprising retractive members extending outwardly from the

oven and to which the door is pivotally connected, said members being adapted to support the door when opened in a substantially horizontal position.

14. In an oven construction the combination of a front frame member having an oven door opening, an oven door and retractive members extending outwardly from the oven and to which the door is pivotally connected, said members being adapted to support the door when opened to a substantially horizontal position and spring members acting on the retractive members to close the door.

15. In a stove oven construction the combination of a front frame member, a door for closing and opening the front frame member, a pair of members extending through the front frame member to which the door is pivotally attached, said members resting on the front frame whereby they may support the door in a substantially horizontal position when opened and resilient means acting on said members to maintain the door closed when the latter is swung to an oven closing position.

16. In a stove oven construction the combination of a front frame member having a door opening, a door for closing said opening, a pair of members extending through the front frame member to which the door is pivotally attached, said members resting on the front frame whereby they may support the door in a substantially horizontal position when opened and spring members acting on said members to close the door.

17. In a stove oven construction the combination of a front frame member having door openings, a door therefor, a pair of slidable hinge bars extending through the oven and projecting therefrom through the frame member, the door being pivotally connected to the extensions of these members whereby the edge of the door may bear against the undersides of said member and whereby said members may support the door in a substantially horizontal position when the door is in open position and spring members reacting upon said bars to cause the latter to maintain the door in a closed position when the door is swung to such position.

18. In an oven construction, the combination of a front frame member, a door for closing an opening in said front frame member, and means for pivotally supporting the door, said means being disposed exteriorly of the front frame when the door is open and being adapted to take the reactive force from the door to support the door in an open, horizontal position.

19. In an oven construction, the combination of a front frame member provided with an oven door opening, a swingable door for closing the opening in said front frame

member, and means for pivotally supporting the door, said means being disposed exteriorly of the front frame member when the door is open and shiftable inwardly 5 when the door is closed.

20. In an oven construction, the combination of a front frame member, a door for closing an opening in said front frame member, and having marginal edges thereof 10 lying in a common plane, and means for supporting the door, said means being retractive but extending outwardly from the

front frame when the door is in an open position, there being a pivotal connection between said means and the door exteriorly 15 disposed when the door is open, said means including means for exerting a pull on the door which is normal to the said common plane when the door is in a substantially closed position. 20

In testimony whereof, I hereunto affix my signature.

ALBERT H. TINNERMAN.
